UNITED STATES PATENT OFFICE.

EDWARD P. CALDWELL, OF CHICAGO, ILLINOIS, ASSIGNOR, BY MESNE ASSIGNMENTS, TO THE GRAHAM ELECTRIC COMPANY, OF SAME PLACE.

ACETYLENE-GAS GENERATOR.

SPECIFICATION forming part of Letters Patent No. 651,341, dated June 12, 1900.

Application filed September 9, 1899. Serial No. 729,989. (No model.)

To all whom it may concern:

Be it known that I, EDWARD P. CALDWELL, a citizen of the United States, residing at Chicago, in the county of Cook and State of Illinois, have invented certain new and useful Improvements in Gas-Generators, of which the following is a specification, reference being had to the accompanying drawings.

My invention relates to machines for generating gas by the union of a solid and liquid, and is primarily designed for the production of acetylene gas.

The invention relates to machines of the character shown and described in my pending application, Serial No. 727,751, filed August 19, 1899, and is an improvement upon the devices shown and described in said application.

It has for its object to provide means for preventing the admission of carbid to the water in the generating-chamber at all times when the cap or cover of the carbid-holder is removed, so that if through carelessness on the part of the person charging the machine with carbid such cap or cover is not replaced after the carbid-holder has been filled the machine cannot operate to generate gas which might escape through the uncovered carbid-holder. I accomplish this object by the means shown in the drawings and hereinafter fully described.

That which I believe to be new will be set forth in the claims.

In the accompanying drawings, Figure 1 is a vertical section through the machine, showing the position of the parts with the cap or cover of the carbid-holder removed. Fig. 2 is a similar view showing the cap or cover on the carbid-holder and the parts in the position they assume when the bell or movable portion of the gas-holder has descended to about its lowest position and with both valves in the carbid-holder opened to permit the passage of carbid to the generating-chamber. Fig. 3 is a similar view representing the position of the parts after gas has been generated in sufficient quantity to raise the bell or movable portion of the gas-holder, and Fig. 4 is a section at line $\alpha\alpha$ of Fig. 3.

Referring to such drawings, A represents

the fixed portion of a gas-holder adapted to contain water, as usual, and B represents the ordinary bell or movable portion of such holder within the fixed portion.

C represents the gas-generating chamber, 55 located below the gas-holder, and which in the construction shown is formed integral with the fixed portion A of such holder, the two being separated by a horizontal wall a . The bottom b of the generating-chamber C is 60 formed on an incline, as shown, in order that the refuse from the used carbid may be directed thereby to one side of the chamber and be the more readily drawn off or taken out through a suitable opening in the side of the 65 chamber. As shown, an ordinary cock c is inserted through the wall of such chamber at a point opposite the lower end of such inclined bottom, through which cock the refuse matter may be drawn off.

D represents a carbid-holder in the form of a large tube, the lower end of which is open and communicates with the chamber C through an opening in a lateral extension of the horizontal dividing-wall a . The carbid-holder, as shown, projects a short distance into the chamber C, so that its open lower end is below the surface of the water in such chamber, by reason of which such end is sealed and to a large extent prevents gas from 80 entering the holder. The upper end of the carbid-holder is closed by a cap or cover d , which, as shown, is screw-threaded onto such upper end.

E E' indicate two valves within the carbid-holder, pivoted at opposite points to the wall of the holder and adapted, when swung across said holder, to retain such carbid as may be placed therein. These valves are normally held closed by two coiled springs e , 85 each fastened at its lower end to one of said valves and at its upper end fastened by an adjusting-screw to a suitable cross-bar e' . With the cap or cover d removed the tension of the springs can readily be regulated by 90 means of the adjusting-screws referred to. These springs, as shown, are crossed, and as the valves are opened and closed from time to time the springs, of course, are extended and retracted, and such action of the springs 100

produces an agitation of the carbid that surrounds them, and thus tends to loosen the mass, so that it will feed more easily to the chamber C.

5 F F' indicate two valve-rods, attached at their upper ends to the valves E E', respectively, and at their lower ends are pivoted at e³ e³ to two levers G' G, respectively, located within the generating-chamber C. At the 10 outer ends of the levers G' G—that is, at the ends near the wall of the chamber C—there are attached by pivots f' f', respectively, rods f² f³, which rods project upward and near the upper end of the carbid-holder D enter 15 such holder. As shown, such rods f² f³ are suitably inclosed in a passage f⁴, that extends from near the upper end of the carbid-holder to a lateral extension f⁵ of the chamber C, and as this extension f⁵ is of course 20 filled with water a seal is provided against gas in any considerable amount escaping therethrough to the carbid-holder. To the opposite ends of the levers G' G' there are pivoted, respectively, by pivots g' g' vertical 25 rods H H', which each pass up through an opening in the horizontal wall a and through pipes h h', respectively, which pipes project beyond the surface of the water in the gas-holder and serve as guides for the rods H H'. 30 As shown, each of these rods is long enough to be acted upon by the top of the bell or movable portion B before such bell or movable portion reaches the limit of its descent. It will also be seen that such rods are of 35 equal length, so that one so projects as to be acted upon by the bell or movable portion before the other is acted upon.

I is a pipe open at its lower end only and communicating through an opening in the 40 horizontal wall a with the chamber C. Near the top of said pipe is suitably secured a short section of pipe i, communicating at one end with the interior of the pipe I and depending, so that its other end is below the surface 45 of the water in the gas-holder.

J is a passage for gas from the gas-holder and, as shown, is formed of a piece of pipe of large diameter open at both ends and passing through suitable openings in the horizontal 50 wall a and the inclined bottom b of the gas-generating chamber C. Its upper end opens into the gas-holder above the water therein, and its lower end opens into a receptacle K beneath the inclined bottom b, 55 such receptacle and the passage J both being adapted to contain a supply of charcoal or other suitable matter adapted to purify the gas.

L indicates a pipe leading from the receptacle K and intended to convey the gas generated in the chamber C to the place of consumption.

In the use of this machine when the carbid-holder is to be filled the cap or cover d thereof is to be removed for such purpose, and immediately upon its removal the rods f² f³,

the upper ends of which have been bearing against such cap or cover, will be moved upward so that such upper ends will project beyond the now open upper end of the carbid-holder, as indicated in Fig. 1. They are caused to so move upward and project by the weight of the vertical rods H H' bearing down upon the inner ends of the levers G' G', which levers turn freely upon their pivots e² e³, and as such levers are not held fixed at either end until their limit of movement is reached it is evident that no downward pressure on the valves E E' is brought to bear sufficient to overcome the pull of the springs e' e' and that 75 therefore the valves will remain closed and no carbid be admitted to the gas-generating chamber C. It is therefore evident that until the levers G' G' are held fast at one end and a downward pressure is applied at the 80 opposite end sufficient to overcome the pull of the springs the machine cannot be operated, as no carbid can be fed to the water in the generating-chamber. To place the machine in operative condition, it is necessary 85 to secure the cap or cover d in place. When such cap or cover is placed over the top of the carbid-holder, it will of course come in contact with the projecting upper ends of the rods f² f³, and as such cap or cover is moved 90 down to tightly close the carbid-holder such rods f² f³ will of course be forced down and firmly held. As these rods are being so forced down the vertical rods H H' are held against upward movement by the weight of the bell 95 or movable portion B of the gas-holder. The consequence is that a strong downward pull is exerted on the valve-rods F F', sufficient to overcome the springs e' e', allowing the valves 100 to open and discharge a quantity of carbid 105 into the chamber C, (see Fig. 2,) where it comes into contact with the water in such chamber, and gas, being at once evolved, rises through the pipe I and, passing through the pipe i, enters the gas-holder. The pressure of the gas on the bell or movable part 110 B raises such part B, and as it rises the rods H H' are also raised through the action of the springs e' e' on the valves E E', the force 115 of such springs closing the valves and shutting off the supply of carbid to the chamber. As the gas so evolved is drawn off for consumption the bell or movable part B of course descends as usual and as it nears its lowermost position comes in contact with the longer 120 of the two vertical rods—to wit, rod H—and forces it down, the effect being, through the lever G and rod F', connected therewith, to cause the valve E' to be pulled down and allow a small quantity of carbid to fall into 125 the water in the chamber C. Now if gas in sufficient quantity be evolved by the carbid so released from the holder the pressure will of course raise the bell or movable part B, releasing the pressure on the rod H, allowing 130 the spring a' to close the valve E', and shutting off the supply of carbid. If, however,

not enough carbide is delivered by the opening of the valve E' to generate a sufficient quantity of gas, the further sinking of the bell or movable portion B will bring its top 5 also in contact with the upper end of the shorter rod H' and through its lever G' and rod F will open the valve E, and both valves being thus opened will allow carbide to descend in quantity sufficient to immediately 10 generate a supply of gas, the pressure of which will raise the bell or movable portion B, both valves being closed, of course, by the action of their respective springs e e' immediately upon the pressure on the bell being removed from the upper ends of the rods H H'. 15

By pivoting the levers G G' to rods that are movable when the cap or cover of the carbide-holder is removed and are stationary only when such cap or cover is in place a machine 20 for generating acetylene gas is provided in which all danger from gas escaping in any considerable quantity through carelessness in neglecting to close the carbide-holder after filling is obviated.

25 That which I claim as my invention, and desire to secure by Letters Patent, is—

1. In a machine for generating gas by the union of a solid and a liquid, the combination with the gas-holder consisting of a fixed and 30 movable portion, of a gas-generating chamber communicating with said gas-holder and adapted to contain water, a solid-containing holder communicating with the gas-generating chamber and having an opening for 35 the insertion of solid material, a removable cover for said opening, a valve in said holder, a lever for controlling said valve, means for operating said lever by the movement of the movable portion of the gas-holder, and a device 40 attached to said lever and extended therefrom in position to be acted on by said cover, to maintain said lever in operative position when said cover is in place, and to move when said cover is removed, to render said lever 45 inoperative, substantially as and for the purpose specified.

2. In a machine for generating gas by the union of a solid and a liquid, the combination with a gas-generating chamber, of a solid-containing holder communicating with said gas-generating chamber, a movable cap or cover therefor, a valve in said holder, a lever for controlling said valve, mechanism for moving said lever, and means for shifting the fulcrum of said lever when said cap or cover is removed, substantially as and for the purpose specified.

3. In a machine for generating gas by the union of a solid and a liquid, the combination 60 with a gas-holder consisting of a fixed and a movable portion, of a gas-generating chamber communicating with said gas-holder and adapted to contain water, a solid-containing holder communicating with the gas-generating chamber, a valve in said holder, a rod 65

attached at one end to said valve, a pivoted lever to which said valve-rod is attached at its other end, means for operating said lever through the downward movement of the movable portion of the gas-holder, and a shiftable 70 fulcrum for one end of said lever, substantially as and for the purpose specified.

4. In a machine for generating gas by the union of a solid and a liquid, the combination with a gas-holder consisting of a fixed and a movable portion, of a gas-generating chamber communicating with said gas-holder and adapted to contain water, a solid-containing holder communicating with the gas-generating chamber, a valve in said holder, a rod 80 attached at one end to said valve, a pivoted lever to which said valve-rod is attached at its other end, means for operating said lever through the downward movement of the movable portion of the gas-holder, a cap or cover 85 for the said solid-containing holder, and means for shifting the fulcrum of said lever when said cap or cover is removed so as to prevent said valve from being operated by the ordinary operation of the machine, substantially as 90 and for the purpose specified.

5. In a machine for generating gas by the union of a solid and a liquid, the combination with a gas-holder consisting of a fixed and a movable portion, of a gas-generating chamber communicating with said gas-holder and adapted to contain water, a solid-containing holder communicating with the gas-generating chamber, a valve in said holder, a rod 95 attached at one end to said valve, a pivoted lever to which said valve-rod is attached at its other end, a second rod also attached to said lever and adapted to be engaged by the movable portion of the gas-holder, and a shiftable fulcrum for one end of said lever, 100 substantially as and for the purpose specified.

6. In a machine for generating gas by the union of a solid and a liquid, the combination with a gas-holder consisting of a fixed and a movable portion, of a gas-generating chamber communicating with said gas-holder and adapted to contain water, a solid-containing holder communicating with the gas-generating chamber, a removable cap or cover therefor, a valve in said holder, a rod attached at 110 one end to said valve, a pivoted lever to which the other end of said valve-rod is attached, and a rod to which one end of said lever is pivoted, said rod extending to and bearing 115 against said removable cap or cover, substantially as and for the purpose specified.

7. In a machine for generating gas by the union of a solid and a liquid, the combination with a gas-holder consisting of a fixed and a movable portion, of a gas-generating chamber communicating with said gas-holder and adapted to contain water, a solid-containing holder communicating with the gas-generating chamber, a removable cap or cover therefor, a valve in said holder, a rod attached 125 130

at one end to said valve, a pivoted lever to
which the other end of said valve-rod is at-
tached, a rod to which one end of said lever
is pivoted, said rod extending to and bearing
5 against said removable cap or cover, and a
passage extending from the gas-generating
chamber to the solid-containing receptacle in

which said last-named rod is located, sub-
stantially as and for the purpose specified.

EDWARD P. CALDWELL.
